UNITED STATES PATENT OFFICE

110,691

DESIGN FOR A BOTTLE CARRYING CASE

Robert E. Dudley, Wellesley, Mass., assignor to The Moxie Company, Boston, Mass., a corporation of Massachusetts

Application February 21, 1938, Serial No. 75,308

Term of patent 14 years

To all whom it may concern:

Be it known that I, Robert E. Dudley, a citizen of the United States of America, residing at Wellesley, in the county of Norfolk and Commonwealth of Massachusetts, have invented a new, original, and ornamental Design for a Bottle Carrying Case, of which the following is a specification, reference being had to the accompanying drawing, forming a part thereof.

The figure is a perspective view of a bottle carrying case embodying my new design.

I claim:

The ornamental design for a bottle carrying case, substantially as shown.

ROBERT E. DUDLEY.
